POST

George A. Gleason, Worcester, Mass., assignor to
 The American Steel and Wire Company of New
 Jersey, a corporation of New Jersey

Application March 15, 1937, Serial No. 131,092

2 Claims. (Cl. 189—23)

This invention relates to posts that are particularly well suited to support highway guard rails.

One of the objects of this invention is to provide a sturdy, easily fabricated post that is adapted to be readily anchored in the ground.

The above and further objects will be made apparent by reference to the following description and the accompanying drawing, in which:

10 Figure 1 is an elevation of the device of the invention;

Figure 2 is a side elevation, partly in section, of the device of Figure 1; and,

15 Figure 3 is a transverse sectional elevation on line III—III of Figure 1.

Referring more particularly to the drawing, the numeral 2 indicates generally a post which includes a channeled member 4 having a body-portion 6 and sides 8 and 9. The channeled member 4 is easily fabricated from a sheet of steel, or other similar material. It will be understood that, if desired, the member 4 may be hot-rolled to shape. The sides 8 and 9 slant outwardly from the body-portion 6 so that the channel member 4 is roughly V-shaped in cross-section and functions to aid in holding itself against undesired movement after once being positioned. A plurality of holes 10 are formed in the channeled member 4 to aid in securing a highway guard cable, or other wire, thereto.

In order to facilitate anchoring the post 2, a bearing-plate 12 is welded, or otherwise secured, between the sides 8 and 9 adjacent one end of the post. The bearing-plate 12 ordinarily should completely fill the space between the sides 8 and 9, as shown in the drawing. When the end of the post 2, carrying the bearing-plate, is placed and driven with a few blows into the ground and packed in with earth, the post 2 is, in most cases, 40 suitably anchored without the use of a concrete base-anchor or a similar anchoring device.

The channeled member 4 can be used without the bearing-plate 12, if the post is to be anchored by other means or if the post does not need to be positively anchored.

While I have shown and described a specific embodiment of the invention, it will be understood that I do not wish to be limited exactly thereto, since various modifications may be made 50 without departing from the scope of the invention, as defined in the following claims.

I claim:

1. The combination of a metallic post consisting of a body member having a ground-engaging portion associated therewith at a spaced distance from the bottom end thereof, the lower portion of said body member disposed in a hole in the ground with said ground-engaging portion disposed in the hole below the ground level and forced against the ground at the bottom thereof as the post is driven thereinto so as to impact 10 the earth at the bottom of said hole to provide a firm foundation therefor, the portion of the body member positioned below the ground-engaging portion extending into the earth below the bottom of said hole and serving as a means 15 for directing and guiding the post thereinto and for holding the same temporarily in position therein so that the ground filled into said hole afterwards around the lower portion of the post and impacted upon the top side of said ground-engaging portion will cooperate therewith to securely hold the post in place and resist any force tending to remove it therefrom.

2. The combination of a metallic post consisting of a channeled body member having substantially a V-shaped cross section, and having a V-shaped bearing plate corresponding to the cross section of the channel portion of said body member secured therein at a predetermined spaced distance from the bottom end thereof 25 with the lower portion of said body member inserted in a hole in the ground, said bearing plate disposed in the hole below the ground level and forced against the ground at the bottom thereof as the post is driven thereinto so as to impact 30 the earth at the bottom of said hole to provide a firm foundation for the post, the portion of the body member positioned below the bearing plate extending into the earth below the bottom of said hole and serving as a means for directing and guiding the post thereinto and for holding the same temporarily in position therein so that the ground filled into said hole subsequently 35 around the lower portion of the post and impacted upon the top side of said bearing plate will cooperate therewith to securely hold the post in place and resist any force tending to remove it therefrom.

GEORGE A. GLEASON. 50
